DESIGN FOR A DISPLAY CONTAINER FOR JEWELRY OR SIMILAR ARTICLES

John Guttman, Brooklyn, N. Y., assignor to Arrow Manufacturing Company, Inc., Hoboken, N. J., a corporation of New Jersey

Application February 29, 1936, Serial No. 61,425

Term of patent 7 years

To all whom it may concern:

Be it known that I, John Guttman, a citizen of the United States, residing at Brooklyn, New York city, in the county of Kings and State of New York, have invented a new, original, and ornamental Design for a Display Container for Jewelry or Similar Articles, of which the following is a specification, reference being had to the accompanying drawing forming a part thereof.

Figure 1 is a perspective view of a display container for jewelry or similar articles showing my new design in closed position.

I claim:

The ornamental design for a display container for jewelry or similar articles as shown.

In testimony whereof I affix my signature.

JOHN GUTTMAN.
